CLAIM

The ornamental design for a hot curling iron tote, as shown and described.

DESCRIPTION

FIG. 1 is a front elevational view of the hot curling iron tote of the present invention;

FIG. 2 is a rear elevational view of the hot curling iron tote of FIG. 1;

FIG. 3 is a left side elevational view of the hot curling iron tote of FIG. 1; the right view being a mirror image thereof;

FIG. 4 is a top plan view of the hot curling iron tote of FIG. 1; and,

FIG. 5 is a bottom plan view of the hot curling iron tote of FIG. 1.

The broken lines showing of a curling iron in FIG. 1 are for illustrative purposes only and form no part of the claimed design. The hollow interior of the tote shown in FIG. 4 is plain and ornamental and forms no part of the claimed design.
